UNITED STATES PATENT OFFICE

166,029

ROOF MOUNTING BRACKET FOR AUTOMOBILE VISORS

Richard E. Dieterich, Long Beach, Ind.

Application August 7, 1951, Serial No. 16,193

Term of patent 14 years

(Cl. D14—6)

To all whom it may concern:

Be it known that I, Richard E. Dieterich, a citizen of the United States and resident of Long Beach, in the county of La Porte and State of Indiana, have invented a new, original, and ornamental Design for a Roof Mounting Bracket for Automobile Visor, of which the following is a specification, reference being had to the accompanying drawings forming a part thereof.

Fig. 1 is a perspective view of a roof mounting bracket for automobile visor, showing my new design.

Fig. 2 is a side elevational view of the same.

Fig. 3 is a top plan view of the same.

Fig. 4 is another perspective view of the same.

Fig. 5 is a front-on perspective view of the same.

Fig. 6 is an elevational view of the same taken from the side opposite to that shown in Fig. 2.

I claim:

The ornamental design for a roof mounting bracket for automobile visor, substantially as shown.

RICHARD E. DIETERICH.
